UNITED STATES PATENT OFFICE

164,253

COMBINED POWDER DISPENSER AND DRINK MIXER

Louis Myers, Rockford, Ill.

Application May 9, 1949, Serial No. 2,532

Term of patent 7 years

(Cl. D44—1)

To all whom it may concern:

Be it known that I, Louis Myers, a citizen of the United States, residing at Rockford, in the county of Winnebago and State of Illinois, have invented a new, original, and ornamental Design for Combined Powder Dispenser and Drink Mixer, of which the following is a specification, reference being had to the accompanying drawings, forming part thereof.

Fig. 1 is a front perspective view of a combined powder dispenser and drink mixer, showing my new design, it being understood that both sides of the unit are alike; and

Fig. 2 is a top plan view thereof.

I claim:

The ornamental design for a combined powder dispenser and drink mixer, substantially as shown and described.

LOUIS MYERS.
